Des. 211,735
Patented July 23, 1968

211,735

CONTROL PANEL FOR A TAPE CARTRIDGE UNIT

James W. Kelso, Los Angeles, Calif.
(1061 Chautauqua, Pacific Palisades, Calif. 90272)

Filed Apr. 26, 1967, Ser. No. 6,854

Term of patent 14 years

(Cl. D26—14)

FIGURE 1 is a front view of the control panel for a tape cartridge unit of the present invention;

FIGURE 2 is a top view;

FIGURE 3 is a bottom view;

FIGURE 4 is a right side view; and

FIGURE 5 is a left side view.

I claim:

The ornamental design for a control panel for a tape cartridge unit, as shown and described.
